UNITED STATES PATENT OFFICE

EMIL A. TAPPERT, OF CHICAGO, ILLINOIS

VENTILATOR

Application filed May 31, 1929. Serial No. 367,358.

My invention relates to a ventilator and has particular reference to a type of ventilator which is adapted for use at the ridge of a skylight, whether the skylight is used as an entire roof of a building, such as a garage or the like, or whether it is used as a unit for admitting light through the roof of a larger building.

Another and further object of my invention is the provision of a ventilator which is capable of being adjusted to varying positions so that an adequate change of air can be secured in a building without the creation of unnecessary drafts or the admission of outside air in the form of drafts and the like.

Another and further object of my invention is the provision of a ventilator which is especially constructed to allow the air in a building or roof portion of the building to pass out of the building without admitting a large quantity of outside air through the ventilator or allowing currents of air to pass into the ventilator from the outside and preventing the movement of air out of the building.

Another and further object of my invention is the provision of a ventilator which is placed at the ridge of the roof so that the warm air of the building rising up toward the roof will pass out and be replaced by air below the roof portion so that a constant change of air is effected in the building without drafts.

Another and further object of my invention is the provision of a skylight ventilator in which it is not necessary to move any portion of the glass forming the skylights, such as is common in the ordinary skylights now in present use and therefore mechanical devices for the lifting of these glass panels is not necessary.

These and other objects of my invention will be more fully and better understood by reference to the accompanying drawings, and in which—

Figure 1 is a side elevational view of my improved invention;

Figure 2 is a plan view of my improved device;

Figure 3 is a longitudinal sectional view on lines 3—3 of Figure 2; and

Figure 4 is a transverse sectional view on lines 4—4 of Figure 2.

Referring now specifically to the drawings and in which like reference characters refer to like parts throughout, a curb 10 is shown which may be of any desired form, and is adapted to rest upon the tops of the walls of a building adapted to have roof portions of glass, and corresponds in general to the roof purlines in a building, or where a skylight is constructed upon the roof of a building, the curb 10 is supported by the roof structure itself.

This curb portion as shown is a specially formed structure for skylight construction and consists of a base portion 11, a riser 12, and an upper portion 13 which is adapted to receive the lower edge of the pane of glass forming the skylight section. A gutter 14 is formed for the purpose of receiving condensation which may collect on the underside of the skylight panes, holes being provided through the riser so that this condensate can run out on the outer portion of the curb 10.

Pairs of jack bars 15, 15 are provided at each end of the building, the outer ends of which are mounted upon the portion 13 of the curb 10, and rest against a hollow rectangular member designated as a whole as 16. This member 16 has a pair of end walls 17 and 18 to which strips 19, 19 are secured in any suitable manner and are turned upon themselves and bowed out at their upper sides so that a flange 20 is formed for the purpose of preventing dust, dirt and the like blowing over the upper edge of the member 17 and downward into the building.

The member 16 has a pair of side walls 21 and 22 respectively, these walls being bent outward at their lower ends so that ledges 23, 23 are formed thereon upon which the ends of the bars hereinafter described are adapted to rest. A pair of angles 24, 24 are secured to the upper edge of the side walls 21 and 22 respectively and project outward therefrom so that dirt which lodges upon the skylight and is blown up against the

walls 21 and 22 is prevented from being blown into the building by the members 24 which catch it and deflect it downward toward the roof.

5 A plurality of hip bars 25, 25 is provided, these bars being mounted at the corners of the curb and extend upward into engagement with the corners of the rectangular member 16. A plurality of common bars 26, 26 are 10 provided which are mounted upon the curb 10 at their lower ends and upon the ledges 23 of the side walls 21 and 22 at their upper ends. The number of these common bars will depend upon the height, weight and span 15 of the building. The upper ends of the jack bars 15 and the hip bars 25 all of which join at substantially a common point, may be joined together in any manner desired.

20 Glass skylight members 27, 27 are provided and which are mounted at their sides upon the diagonally extending bars heretofore described; and which are supported by the curb at their lower portions and by the overhanging ledges 22 and 23 at their upper portions. 25 This is the usual manner of mounting the glass sections in skylight frames and has nothing to do with my present invention.

25 A cap 28 is provided which is rectangular in shape and may be of any desired shape so long as it conforms to the substantial dimensions of the member 16 over which it is adapted to fit. A plurality of vertical bars 29, 29 are provided which are secured at their 30 upper ends to the member 28 and whose lower ends are mounted in guideways 30, 30 which are secured to the inner sides of the side walls 21 and 22 respectively. Extending 35 transversely across the member 16 and secured to the side walls 21 and 22 respectively, is a pair of bars 31, 31 within which a bar 32 is mounted which is movable longitudinally.

40 Secured to the bar 32 in any approved manner is a pair of toggle arms 33, 33, the upper ends of these members being secured to a pair of T members 34, 34 which are secured in the top of the member 28 in any approved manner. The lower ends of these bars are adapted to engage against the members 31, 31 when in a substantial vertical 45 position and when in such position are adapted to hold the cap 28 a substantial distance above the member 16 so that air or other vapors rising up to the top of the skylight 50 can pass out between the upper edge of the member 16 and the lower edges of the cap 28. The cap 28 has an annular outwardly 55 projecting portion 35 extending therearound with a downwardly projecting portion 36, the portion 35 being substantially of the 60 same angle of the projecting portions 20 and 24 so as to fit tight thereagainst when the 65 ventilator is closed.

65 A truss 37 is provided which at its central portion has an upper projecting member 38

70 within which a rotatably mounted shaft 39 is positioned. The bar 32 on its underside has a pair of loops 40, 40 secured thereto to which one end of chains 41 and 42 respectively are secured. These loops 40 are spaced a considerable distance from the rotatably mounted shaft 39 which serve the purpose of a pulley over which the chains 41 and 42 may travel. The purpose of the chains 41 and 42 75 is to enable a workman to raise or lower the cap 28 as may be desired, to insure sufficient ventilation in the building. As shown, when the chain 41 is pulled the bar 32 is moved in a horizontal direction to the left (Fig. 3) thereby causing the toggle arms 33 80 to assume an angular position and lowering the cap 28 onto the member 16. When it is desired to raise the cap 16, the chain 42 is pulled, thus moving the bar 32 in opposite direction and moving the arms 33, 33 to a 85 substantially vertical position so that the cap 28 is lifted, thereby allowing air, vapors and the like to pass through the member 16 and out of the building.

90 It will thus be understood that the device while practical for skylight construction, may be inserted in any roof construction where the rectangular member is placed in the roof in place of the usual ridge pole and the ventilating cap secured thereto in such 95 manner that it may be raised or lowered to secure proper ventilation depending upon weather conditions.

95 The device will remain in a wide open position or in any intermediate position, between a wide open and a closed position, due to the friction of the side members in the loops secured to the member 16, and also to the friction of the bar 32 in the members 31 so that it is unnecessary to provide any 100 fastening means for chains 41 and 42.

105 While I have described more or less precisely the details of construction, I do not wish to be understood as limiting myself thereto, as I contemplate changes in form, 110 and the proportion of parts and the substitution of equivalents as circumstances may suggest or render expedient without departing from the spirit or scope of my invention.

115 I claim:

1. A ventilator comprising in combination an open rectangular member, a cap on said rectangular member, connections between said cap and said rectangular shaped member, a slidably mounted bar, arms pivotally connected to said cap and said bar, and manually operable means whereby the said bar is moved longitudinally.

2. A ventilator comprising in combination an open rectangular shaped member, a cap member mounting bars carried by said cap member and slidably mounted in said rectangular member, sliding bar, and toggle arms secured at one end to said sliding bar.

and at their upper ends to said cap member.

3. A ventilator comprising in combination an open frame member, a cap, arms on said cap, loops in said frame member adapted to receive the arms, a movable bar, means whereby the said movable bar is supported, and toggle arms connecting said cap and said movable bar.

4. A ventilator comprising in combination an open frame member, a cap, arms on said cap, loops in said frame member adapted to receive the arms, cross bars carried by said frame member, a slidably mounted bar in said cross bars, and toggle arms connecting said cap and said slidably mounted bar.

5. A ventilator comprising in combination an open frame member, a cap, arms on said cap, loops in said frame member adapted to receive the arms, cross bars carried by said frame member, a slidably mounted bar in said cross bars, toggle arms connecting said cap and said slidably mounted bar, a pair of flexible members secured to said bar, and a supporting member for said flexible members.

6. A ventilator comprising in combination an open frame member, a cap, arms on said cap, loops in said frame member adapted to receive the arms, cross bars carried by said frame member, a slidably mounted bar in said cross bars, toggle arms connecting said cap and said slidably mounted bar, a pair of flexible members attached to the said bar, and a rotary member mounted in said frame member between the points of attachment of said flexible members on said bar and over which each of said flexible members pass.

7. A ventilator comprising in combination an open frame member, a cap, arms on said cap, loops in said frame member adapted to receive the arms, cross bars carried by said frame member, a slidably mounted bar in said cross bars, toggle arms connecting said cap and said slidably mounted bar, a pair of flexible members secured to said bar at spaced points, and a rotary member between said points on the bar.

8. A ventilator comprising in combination an open frame member, a cap, arms on said cap, loops in said frame member adapted to receive the arms, cross bars carried by said frame member, a slidably mounted bar in said cross bars, toggle arms connecting said cap and said slidably mounted bar, and means whereby the said bar is moved.

9. A ventilator comprising in combination an open rectangular member, supporting members therefor, a cap movably supported on said rectangular member, a movably mounted bar, flexible members connected to said bar, the points of connection being in spaced relation with each other, a rotatably mounted member in fixed position between the points of connection of the flexible mem-

bers on the bar, and arms connecting the said movably mounted bar and the said cap.

Signed at Chicago, Illinois, this 22 day of May, 1929.
